UNITED STATES PATENT OFFICE.

FRANJO MALOVICH, OF CHICAGO, ILLINOIS.

DESIGN FOR A CABINET.

Application filed May 25, 1922. Serial No. 2,417. Term of patent 14 years.

To all whom it may concern:

Be it known that I, FRANJO MALOVICH, a subject of the King of Yugoslavia, residing at Chicago, in the county of Cook and State of Illinois, have invented a new, original, and ornamental Design for Cabinet, of which the following is a specification, reference being had to the accompanying drawings, forming part thereof.

Figures 2 and 3 are similar views of the opposite ends thereof.

I claim:-

The ornamental design for a cabinet, as shown.

FRANJO MALOVICH.
